John E. Beardmore, Chicago, Ill., assignor to Karoll's,
Inc., Chicago, Ill., a corporation of Illinois

Filed Feb. 27, 1963, Ser. No. 73,758

Term of patent 14 years

(Cl. D15—1)

FIGURE 1 is a perspective view of a combined mobile lounge chair and removable tray in operating position embodying the features of my new design;

FIGURE 2 is a front elevational view thereof;

FIGURE 3 is a top plan view thereof;

FIGURE 4 is a rear perspective view showing the tray in stored position and the foot rest raised;

FIGURE 5 is a front elevational view of the chair of FIGURE 4; and

FIGURE 6 is a top plan view thereof.

I claim:

The ornamental design for a combined mobile lounge chair and removable tray, substantially as shown and described.
